UNITED STATES PATENT OFFICE.

WILLIAM S. BREWER, OF NEW YORK, N. Y.

MANIFOLD-CHECK DEVICE.

SPECIFICATION forming part of Letters Patent No. 780,857, dated January 24, 1905.

Application filed December 17, 1903. Serial No. 185,488.

To all whom it may concern:

Be it known that I, WILLIAM S. BREWER, a citizen of the United States, residing at New York city, State of New York, have invented 5 certain new and useful Improvements in Manifold-Check Devices, of which the following is a clear, full, and exact description.

My invention relates to a duplicate-check system—that is, to one in which the matter 10 written upon an "original" or main check is entirely or in part simultaneously duplicated on a "duplicate" or secondary check; and my object is to improve and simplify such constructions.

15 My invention will be pointed out in the claims.

In the drawings, which show preferred forms of my invention, Figure 1 is a plan view; Fig. 2, a side view looking from left 20 to right in Fig. 1. Figs. 3 and 4 are plan and side views of a modification. Fig. 5 is an end view of Fig. 1, showing a modified shape of retaining-post. Figs. 6 and 7 are plan and side views of another modification. 25 Figs. 8 and 9 are side and front elevations of the pivot-post of Fig. 1, and Fig. 10 is a sectional detail of Fig. 1 on line $\alpha\alpha$.

In carrying out my invention I provide a base or back, which preferably consists of 30 two covers hinged in the middle and adapted to hold between them when closed two sets of paper sheets, the same comprising, respectively, the original and duplicate checks or leaves, although other forms of base may be 35 employed, as will be seen hereinafter. The original checks or leaves are superposed—that is, they lie or are adapted to lie one above another—and the leaves or checks of the manifold or duplicate series are also superposed in the form of a pad, and means is 40 provided for transferring an impression upon the original check to the underlying duplicate check, preferably by a suitable transfer or carbon sheet on top of the pad, and means are provided whereby any one of the originals may be caused to lie upon the transfer-sheet without detaching any of said original checks from the base. The waiter then writes 45 the entire order on the original check, thus 50 also making a duplicate order or a partial

duplicate order on the duplicate check lying underneath the transfer-sheet. Other features embraced in but not essential to my invention will be described in a subsequent portion of this specification.

Referring now particularly to Figs. 1, 2, and 10, the base or back comprises two covers 1 and 2, attached together by a flexible portion 3 or otherwise hinged together, so that they may be folded over upon each other. 55 4 is the pad of manifold or duplicate checks or leaves. These are preferably loose paper sheets superposed one on another like the leaves of a book and attached to the base at one edge only of the pad. The pad may be 60 attached to the base at different points and still be within my invention; but I prefer to attach the left side of the pad to the left side of the base, as shown. I preferably attach the pad by perforating it with two holes, 65 through which pass posts 5 and 6 on the base; but it will be obvious that such a construction is only one of many pad-holding devices which might be devised. A locking means for preventing accidental removal of the 70 sheets or of the transfer-sheet 7, which lies on top of the pad, may be provided, and in Fig. 1 I have shown the posts 5 and 6 cut away to form a head thereon, as shown in Figs. 5 and 10, and two spring-wires 8 and 9 attached to the 75 base, which press down upon a perforated follower-strip of metal 10, which rests on top of the transfer-sheet, the ends of the wires being located under the heads on the posts, as seen in Figs. 5 and 10, thus locking the sheets 80 in place and continually pressing the transfer-sheet down upon the pad. The sheets of the pad are preferably unattached to each other and made of some weak paper, so that a slight pull on a sheet will tear it away from 85 the posts. The right edge of the pad is preferably beveled, as in Fig. 5, so that the upper sheets project slightly beyond those underneath, so that the upper one may be more easily raised off from the others. This beveling may be accomplished by cutting the pad to this shape or by inclining or tapering the posts, as seen in Figs. 5 and 10.

11 13 represent a set of superposed paper sheets constituting the original checks, said 100

sheets being preferably unattached to each other and held to the base or back, preferably, but not necessarily, by being pivoted to the base so that they may be swung on said pivot 5 and any one of them caused to lie directly on said transfer or carbon sheet, as shown by the sheet 11 in Fig. 1. This pivot for the originals may be a post 14 substantially perpendicular to the base beyond the margin of the 10 pad and passing through holes in the checks, or the pivot may be a loop or ring, as shown at 15 and 16 in Figs. 3 and 6. I may also provide a holder for the original checks, and this is preferably formed by a plate 17 raised 15 above the base and supported by the posts 5 and 6, thus forming a pocket open at the right side and both ends. A holder open at one side and end is also shown at 18 in Figs. 1 and 2. 19, Figs. 3 and 4, and 20, Figs. 6 20 and 7, show other forms of holders or retaining devices for the original checks.

When the set of originals is to be attached to the base, the locking-spring 25 of Fig. 1 is released from the catch on post 14, (see Figs. 25 8 and 9,) the originals slipped over the post, and the spring then reengaged with the catch. The set of originals may then be swung around to the position shown in dotted lines in Fig. 1 and then back into the pocket below 30 plate 17, or they may be swung around into the position of check 12, so as to be retained by the holder 18.

Now if the waiter wishes to take an order he swings the uppermost original check out to 35 the dotted position and then into the position indicated by check 11 and writes the order upon it.

The original checks may be consecutively numbered, (as indicated by "119" on check 40 12 and "120" on check 11,) and each original and duplicate check may also bear a corresponding designation, such as "Waiter 4," and the duplicate checks are preferably consecutively numbered, as "53" for the uppermost 45 duplicate, "54" for the next one, &c. As the waiter starts to write the order he writes the number (*e. g.*, "120") of the original on the margin of the duplicate, as shown. Now if the bar, eatables, and cigars are in separate 50 departments he detaches check "53" after writing the first item, then writes the next two items, and puts "120" on check "54" and detaches it, and so on for each department. He thus has a separate order on each department 55 for those articles, and those only which are furnished by that department, and as the combined duplicate checks marked "120" on the margin must correspond in items to the total on original check "120" of "Waiter 4" 60 the head of each department has a separate order for only what his department has furnished, and the total duplicate checks missing must total the same as the total items on all the original checks used. Thus the auditor of 65 the books has complete track of every item.

It will be obvious that any one of the original checks may be superposed directly on the pad. If, for example, the waiter has taken several other orders since he wrote the first three items on check No. 120, that check will 70 be somewhere in the midst of the used originals held by the retaining device 18, or perhaps it may be in the pocket underneath plate 17; but in either case it can be brought out and swung into position above the pad—in the first 75 case by swinging it from the position of check 12 directly onto the pad and in the second case by swinging the checks above it in the pocket around to the position of check 12 and then swinging check 11 into place on the pad. The 80 cigars and bar orders are then written on the original and a separate duplicate order made on the cigar and bar departments, as before explained. Consequently any original check 85 may be superposed directly on the transferring-sheet and pad without detaching any of the original or duplicate checks from the base.

It will be observed that I have provided two sets of checks—one an original set and the other a duplicate—both fastened to the base 90 and one of said sets (in this case the original set) pivoted so that it may be swung substantially in its plane and that the sheets of the other set are detached from each other except at the edge where they are fastened 95 together, whereby the duplicate set may be caused to lie beneath any one of said originals.

In Figs. 3 and 4 a modification is shown in which the base 21 is merely a metal plate bent up at one end, as shown in Fig. 4, and is not provided with any cover corresponding to the part 2 of Fig. 1. This modification, however, has a pocket formed by plate 17 the same as in Fig. 1, but slightly broader, so as to support thereon two independent pads 4 and 4' of duplicates. It also has a modified form of retaining device for the pads, consisting of spring-strips 22 fastened to the base at one end and perforated at the other end to pass over the retaining-posts. The pivot for the originals is also of modified form, being an elongated loop of wire 15 normally held in the full-line position shown by a spring-catch 23. The originals can thus be swung to the right out of the pocket and onto the pad, or when the loop is in the dotted position they may be swung over on this loop in a plane perpendicular to their face, substantially as in Figs. 6 and 7, and caused to lie against the back of the base, where they may be held by the spring-clip 19. In this modification I have shown the originals as having a weakened line 26 in each, such as a line of perforations lying substantially at the adjacent edges of said pads, so that the original may be easily divided at that point, if desired. 115

Figs. 6 and 7 show a modified form also included in my invention. This form has a two-part base, one of the parts having a plate 17 forming a pocket thereon open at the top, 120

right side, and bottom, a pad 4 of duplicates held by the left edge to the left side of the base above the pocket, and a set of superposed originals pivoted so that they may be swung 5 either to right and left in the plane of their face or in a plane perpendicular thereto, so that any one of them may be caused to lie on top of the pad, substantially as in Fig. 3. The original checks employed with this form of 10 construction should preferably have notches formed in their end edges at the side of their pivot-hole and at such a distance from the pivot-hole as to be adapted to receive therein the opposite side of the pivot ring or staple 15 16 when the checks are swung to the transverse position or at right angles to that occupied when in the pocket. Such notches are shown at 24 in Fig. 6. While I have shown the pivot as being a ring, it is evident that it 20 might be made as a staple and the two parts 1 and 2 of the cover be made as one rigid member, or the hinge 3 may be placed above the staple or ring 16.

I am aware that many variations from the 25 constructions shown may be made without departing from the scope of my invention as claimed, and I therefore do not limit myself to the constructions illustrated and described.

What I claim is—

- 30 1. In a manifold-check device, in combination, a base, a pad of duplicate checks fastened to said base, a transfer-sheet secured on top of said pad, a set of superposed original checks pivoted to said base, whereby any one of said 35 original checks may be swung on said pivot independently of the others and substantially in the plane of said original checks to thereby be brought to lie directly on said transfer-sheet.
- 40 2. In a manifold-check device, in combination, a base, a pad of duplicate checks fastened by an edge to one side of said base, a transfer-sheet secured on top of said pad, a set of superposed original checks pivoted to said base by 45 a pivot passing through them and located beyond the margin of said pad, whereby any one of said originals may be swung on said pivot independently of the others and caused to lie directly on said transfer-sheet.
- 50 3. In a manifold-check device, in combination, a base, a pad of duplicate checks fastened by an edge to one side of said base, a transfer-sheet secured on top of said pad, a set of superposed original checks pivoted to said base by 55 a pivot passing through them and located beyond the margin of said pad, whereby any one of said originals may be swung on said pivot independently of the others and caused to lie directly on said transfer-sheet, and a 60 holder for said original checks when swung on said pivot.
- 65 4. In a manifold-check device, in combination, a base, a pad of duplicate checks fastened by an edge to one side of said base, a transfer- sheet secured to lie on top of said pad, a set

of superposed original checks independently pivoted to said base beyond the margin of said pad and in position to be overlapped on said pad whereby any one of said original checks may be swung on said pivot independently of the others and brought to lie directly on said transfer-sheet, a pocket open at one side and end for the reception of said original checks when swung on said pivot, said pocket being located beneath said pad of 75 duplicate checks.

5. In a manifold-check device, in combination, a base, a pad of duplicate checks fastened by its left edge to the left side of said base, a transfer-sheet adapted to lie on top of the 80 same, a set of superposed original checks independently pivoted to said base on a post located on said base beyond the margin of said pad, whereby any one of said originals may be swung on said post and caused to lie directly on said transfer-sheet.

6. A manifold-check holder comprising a base, a pocket thereon open at one end and the right side, a device at the left side of said base and above said pocket for holding the 90 left edge of a pad of duplicate checks, and a pivot on said base beyond the open edge of said pocket and adapted to pass through holes in the ends of a set of superposed original checks.

7. A manifold-check holder comprising a base, a device at the left side thereof for holding the left edge of a pad of duplicate checks, a pivot-pin on said base beyond the margin of said pad, a set of original superposed checks 100 having holes for the reception of said pivot-pin, whereby said checks may be independently swung on said pivot, said pivot-pin being located at a distance from the edge of the duplicate pad at least equal to the distance of the 105 pin-holes from the edge of the original checks.

8. A manifold-check holder comprising a base, a pair of posts at the left side thereof for holding the left edge of a pad of duplicate checks, said posts having locking means to 110 retain said pad, a pivot on said base beyond another edge of said pad, and a set of original superposed checks having holes adapted to receive said pivot, whereby said checks may be individually and independently swung on said 115 pivot.

9. In a manifold-check device, in combination, a base, a set of original checks, a pad of duplicate checks attached to the said base, a transfer-sheet adapted to lie on top of said pad, 120 and means for holding said set of originals on the base whereby any one of said originals may be superposed directly on said transfer-sheet without detaching any of said checks from said base, each of said original and duplicate checks bearing corresponding designations, and said sheets of said pad being also 125 numbered consecutively.

10. A manifold book or tablet, comprising a back carrying a pivot extending at right angles 130

thereto, a series of sheets of paper, mounted and adapted to turn on said pivot, and another series of sheets of paper independently mounted on said back in such relative position to the 5 pivoted series that when a sheet of the pivoted series is swung round on its pivot it may be brought to register with the other series.

11. A manifold book or tablet, comprising a back carrying a pivot extending at right angles 10 thereto, a series of sheets of paper mounted and adapted to turn on said pivot, and another series of sheets of paper independently mounted on said back in such relative position to the pivoted series that when a sheet of the pivoted 15 series is swung round on its pivot it may be brought to register with the other series, and a carbon-sheet attached to said back in a position to be placed between the juxtaposed sheets of the two series.
12. A manifold book or tablet, comprising a back carrying a pivot extending at right angles thereto, a series of original leaves mounted on 20 said pivot, a series of manifold slips of paper and an impression-sheet independently mounted on said back, each sheet of said pivoted series, independent of the others, adapted to be turned on said pivot and superposed on said manifold series, or independently withdrawn 25 from the said original series.
13. In a manifold-check device in combination, a base, a set of duplicate checks fastened 30

to said base, a set of superposed original checks also fastened to said base, one of said sets being pivoted on said base whereby said set may be swung on said pivot substantially in the plane 35 of said set, the sheets of said other set being detached from each other whereby any one of said original checks may be caused to lie directly upon said duplicate set, and means for transferring to said duplicate set the impression made on the original check which was superposed thereon.

14. In a manifold-check device in combination, a base, a set of duplicate checks fastened to said base, a set of superposed original checks 40 also fastened to said base, one of said sets being pivoted on said base whereby said set may be swung on said pivot substantially in the plane 45 of said set, the sheets of said other set being detached from each other whereby any one of 50 said original checks may be caused to lie directly upon said duplicate set, and a transfer-sheet fastened on said duplicate set for transferring to said duplicate set the impression made on the original check which was superposed thereon.

Signed at St. Louis, Missouri, this 2d day of December, 1903.
